COMBINATION HOLDER

Rikijiro Osaka, New York, N. Y.

Application May 3, 1952, Serial No. 285,867

1 Claim. (Cl. 150—34)

1

This invention relates to combination holders adapted to be carried in the pocket in the manner of a fountain pen with a pocket clip, or otherwise, and the main object is the provision of a new and improved combination holder for, say, a comb and toothpicks, including a larger or longer pocket for the comb and a smaller pocket for the toothpicks, the latter pocket comprising itself a holder which may be readily removed from the main holder and as readily reinserted thereinto.

Another object of the invention is to provide efficient releasable means for locking the removable holder or pocket in the main holder.

It is also an object of the invention to construct the combination holder in such a manner that it may largely be manufactured out of a simple flat pattern.

The above as well as additional and more specific objects will be clarified in the following description, wherein characters of reference refer to like-numbered parts in the accompanying drawing. It is to be noted that the drawing is intended solely for the purpose of illustration, and that it is therefore neither desired nor intended to limit the invention necessarily to any or all of the exact details of construction shown or described except insofar as they may be deemed essential to the invention.

Referring briefly to the drawing,

Fig. 1 is a perspective view showing one form of the combination holder, as it is normally carried by the user.

Fig. 2 is a similar view showing the smaller pocket or holder only partly inserted into its recess on the main holder, and with the flap thereof open, as well as showing the flap of the comb pocket open.

Fig. 3 is an exploded perspective view showing the two flat patterns, partly folded, out of which the combination holder of Fig. 1 may be formed.

Fig. 4 is a perspective view of a modified form of the combination holder, as it is normally carried by the user.

Fig. 5 is a sectional view taken on the line 5—5 of Fig. 4.

Fig. 6 is an exploded perspective view showing the two flat patterns, partly folded, out of which the combination holder shown in Fig. 4 may be formed.

Fig. 7 is a perspective view of an alternative partly folded flat pattern out of which the main holder of the combination holder shown in Fig. 1, may be formed.

Fig. 8 is a perspective view of an alternative partly folded flat pattern out of which the main

2

holder of the combination holder shown in Fig. 4, may be formed.

Referring in detail to the drawing, the numeral 10 indicates the main holder which comprises 5 the back member 11 and the front wall member 12, forming the pocket 13 adapted to receive a comb or the like 14. A closure flap 15 is an extension of the back 11 and is provided with a female snap button member 16 engageable with the male member 17 on the pocket wall 12, to close the pocket 13 over the comb.

Utilizing the lower portion of the wall 12 as a back member, a second pocket 18 is formed by providing a shorter front pocket wall 19 attached 15 or sewed around its edges to the member 12. A small holder 20, adapted to contain toothpicks or the like, is provided in the form of a pocket having a snap button flap 21 bearing the female snap portion 22, the complementary male snap portion 23 being provided on the wall 19. To releasably lock the pocket 20 in the pocket 18, the flap 21 is turned down and the snap member 22 thereon is engaged with the snap member 23 on the wall 19. The pattern member 10a in Fig. 25 3 may be used to form the main holder 10 of Figs. 1 and 2, as is readily apparent, by folding the portions thereof to form the finished holder and sewing along the appropriate edges; the parts of Fig. 3 which form the corresponding parts of the finished holder of Figs. 1 and 2 bear the same reference numerals followed by the suffix "a."

In the modification shown in Fig. 4, the final combination holder is identical to that shown in Figs. 1 and 2, with the exception that the male snap button member 23b of the flap 21b of the removable holder is attached to the front wall 19b of the removable pocket 20b, and an opening 24 is provided through the front wall 25 of the latter through which the male member 23b is projected when the removable holder or pocket 35 40 45 20b is positioned in the pocket 18b. Then, to lock the holder 20b in the pocket 18b, the flap 21b is folded down and the female snap member 22b is snapped on the protruding male member 23b. In this case, also, the front wall 12b extends only partly down from the top of the back 11b.

Fig. 6 shows how the main holder of Fig. 4, that is, all but the removable pocket or holder 20b, may be formed of the single pattern 10c (at the left), and at the right it shows how the removable holder 20b may be formed of the pattern 20c.

Fig. 7 shows an alternative pattern out of which the main holder of Figs. 1 and 2 may be formed, and Fig. 8 shows an alternative pattern

out of which the main holder of Fig. 4 may be formed.

In all the views, where a reference numeral is followed by a suffix such as "b," "c," "d" or "e," such numerals refer to the same or equivalent parts of the finished combination holders of Figs. 1, 2, or 3.

It is apparent that the various patterns illustrated would serve to form the various holders or holder parts in a very simple manner, by sewing or otherwise attaching appropriate edges together.

Obviously, modifications in form or structure may be made without departing from the spirit or scope of the invention.

If it is desired to carry the combination holder in the pocket of a coat in the fashion of a fountain pen, a clip 26 of standard construction may be provided on the back of the back member 11 or 11b, near the upper end thereof.

I claim:

A combination holder comprising an elongated back member having a shorter front wall of like width secured around the edges thereof to the back member except for the top edge thereby forming a pocket open at the top, said back member extending above said top edge thereby forming a pocket flap adapted to fold down over the top of said front wall, means for releasably locking said flap against said front wall in folded down position of the flap, a second front wall of

the same width as said first front wall but having a substantially shorter length than the first front wall attached around the edges thereof to the corresponding edges of the lower portion of said back member except for the top edge of said second front wall thereby providing a second and smaller pocket, a removable holder having a pocket therein insertible into said smaller pocket, said removable holder having a cover flap thereon adapted to be folded down over the top of said second front wall, and means for releasably locking said second front wall and said last-named flap together when said removable holder is positioned in said second pocket, said last-named means comprising a female snap button on said last-named flap and a male snap button on the front of said removable holder, said second front wall having an opening therethrough, said male snap button projecting through said opening and being engageable by said female snap button of said last-named flap.
